UNITED STATES PATENT OFFICE.

THEODOR KUNDTZ, OF LAKewood, OHIO, ASSIGNOR TO THE THEODOR KUNDTZ COMPANY, OF CLEVELAND, OHIO, A CORPORATION OF OHIO.

DESIGN FOR A SEWING-MACHINE CABINET.

49,151.

Specification for Design.

Patented June 6, 1916.

Application filed April 10, 1916. Serial No. 90,263. Term of patent 7 years.

To all whom it may concern:

Be it known that I, THEODOR KUNDTZ, a citizen of the United States of America, residing at Lakewood, in the county of Cuyahoga and State of Ohio, have invented and produced a new, original, and ornamental Design for a Sewing-Machine Cabinet, of which the following is a specification, reference being had to the accompanying drawing, forming part thereof.

The figure is a perspective view of a sewing machine cabinet showing my new design.

I claim:

The ornamental design for a sewing machine cabinet as shown.

THEODOR KUNDTZ.
